UNITED STATES PATENT OFFICE.

PETER AMATO, OF LYNN, MASSACHUSETTS.

LOUD-SPEAKER UNIT.

Application filed May 5, 1926. Serial No. 106,912.

- This invention relates to new improvements in sound reproducing apparatus, and particularly to an electrically operated loud speaker unit.
- 5 This invention comprehends the provision of a new principle of construction and operation of a loud speaker unit in order to eliminate the numerous disadvantages inherent in loud speaker units, now known to 10 the art, resulting from the mechanical construction and association of the parts.

It is an object of this invention to provide a loud speaker unit wherein a sound reproducing plate member is freely supported for 15 uniform reciprocating movement on its axis in order to move a column of air to produce sound waves corresponding to the vibratory reciprocation of this reproducing member.

A further object of the invention resides 20 in providing a loud speaker unit for reproducing sound waves including a vibratory armature adapted to be vibrated by suitable electro-magnetic means having a single support extending laterally relative to the axis 25 of movement of the armature with a sound reproducing member directly and axially connected with the armature.

A further feature of the invention resides 30 in providing means for varying the relation between the sound reproducing assembly and the operating structure therefor, in order that the volume of the reed production may be directly controlled.

The invention comprehends numerous 35 other objects residing in the method of constructing and mounting the reproducing structure or assembly and the operating unit therefor, which are more particularly pointed out in the following detailed description, 40 and in the claim directed to a preferred form of construction, it being understood, however, that various changes in the size, shape, and arrangement of the parts may be made without departing from the spirit and 45 scope of the invention as herein set forth.

In the drawings forming part of this application:

- Figure 1 is a rear elevational view of the assembled reproducer.
- 50 Fig. 2 is a vertical transverse section thru the reproducer as shown in Fig. 1.
- Fig. 3 is a side elevation of the assembled reproducing and operating units therefor,
- 55 Fig. 4 is a horizontal sectional view taken on the line 4-4 of Fig. 3, showing the structure of the operating unit and the armature of the reproducing assembly.

Fig. 5 is a front elevation of the construction shown in Fig. 4, showing the armature construction and mounting for the reproducing assembly in its associated relation with the operating structure.

A suitable fork or standard is indicated at 1 which carries at its upper end a cylindrical housing 2 provided with an open forward end having the annular flange 3 extending therefrom.

The sound reproducing assembly includes the armature 4 which includes the vibratory section 5 connected by a narrow strip portion 6 with the supporting plate portion 7 forming the single support for the entire sound reproducing assembly which is mounted by suitable means indicated at 8 on the flange 3 of the housing 2. A suitable axis 75 rod 9 is secured at one end to the center of the vibratory section 5 of the armature as clearly shown in Fig. 5, while the opposite end extending in axial relation with respect to the axis of movement of the vibratory section 5 carries the reproducing member 10. This reproducing member 10 includes a frame work 11 composed of a plurality of radially extending bars 12 formed with tapered inner end portions at 13, having these 85 tapered spaces in intimate contact and securely assembled relation in forming a unitary and substantially rigid frame construction.

The bars 12 are of substantially uniform 90 width throughout their length beyond the tapered ends 13, while in thickness they vary as more clearly shown in Fig. 2, from the inner ends at 13 which are of greater thickness to the outer end indicated at 14 which are of minimum thickness. A reproducing plate member 15 of suitable cheap material is applied to one face of the frame structure as shown in Fig. 2, which lies within a normally plane surface while the variation in 95 thickness of the members 12 is provided for on the opposite face of the frame structure. After the application of the reproducing plate member 15, to the frame structure 11, a pair of assembling disks 16 are positioned against opposite sides of the central portions of this sound reproducing assembly or unit and are formed with central openings to receive the axis rod 9 to which the entire unit is rigidly secured by the securing 100 105 110

means indicated at 17, locking the assembling disks, the frame, and plate member 15 in rigid assembled relation on the axis rod. This completes the construction of the sound reproducing structure of the loud speaker unit which is mounted on the single support through the plate 7 carrying the vibratory section 5 so that the sound reproducing assembly is freely movable with the vibratory section.

In this way, a full floating sound reproducing assembly is provided which is carried by the vibratory armature section 5 which directly moves the entire air column with the movement of the reproducing plate member 15, for setting up the sound waves. Due to the full floating movement of the reproducing assembly, the sound waves produced will be uniform throughout the entire area due to the fact that the plate member 15 will reciprocate or vibrate uniformly throughout its entire area through the association and construction of the frame assembly 10.

25 By this construction of the reproducing assembly being supported with the single support which carries the armature and the vibratory section thereof, it will be seen that the vibratory section and reproducing plate 30 operate in unison which eliminates the transmission of mechanical noise or the production of rattling causing the reproduction of undesirable sound with the sound reproduction.

35 An operating unit is mounted in the housing 2 for operating the full floating sound reproducing mechanism and includes a casting 18 slidably mounted within the housing and preferably formed of suitable non-magnetic metal. The pole pieces of the magnet structure are indicated at 19 having the separate terminals 20 of angular formation as shown in Fig. 4, removably assembled therewith through the means of bolt and nut 40 connections 21 which secure the pieces 19 together with the terminal pieces 20 in assembled relation in the back of the casing 18, as shown clearly in Fig. 4. These screw members also secure angle brackets 22 to the rear face of the casing 18 which are formed with openings rotatably receiving the operating rod 23 having the eccentric portion 24 mounted in openings in the brackets 22 and the opposite ends rotatably mounted 50 in the housing 2. One end of this member 23 extends outwardly beyond the housing and is provided with a handle section 25 so that the casing 18 may be suitably moved within the housing 2 in order to vary the distance between the ends of the terminal pieces 20 and the vibratory section 5 of the armature. These terminal pole pieces 20 receive

and mount the electro-magnet windings 26 which are adapted to be electrically connected in circuit with a radio receiving set in a manner well known in the art, or with other sound and transmitting and reproducing apparatus for operating the vibratory section of the armature in the energization of the electro-magnet for varying the strength of the magnetic field of the permanent magnet 19 with the pole pieces 20.

The rotation of the handle 25 and the operating member 23 forming part thereof, will serve to control the volume of sound reproduction to a desired degree.

With the full floating reproducing structures above described, the frame member 10 will act to transmit the motion of the axis pin to the entire surface of the reproducing plate member, and thereby form a stress distributing means for the plate member in order to cause the entire structure to vibrate with equal amplitude over the entire surface. This will result in a much greater volume of sound together with a substantially perfect tone quality.

It results from this full floating structure having an equal vibrating amplitude, that all overtones and undertones are properly reproduced resulting in a most natural sound reproduction. There is no distortion in view of the size of the producing unit which moves a substantially large column of air without requiring the use of a horn.

100 This construction in providing a full floating mounting for the sound reproducing structure with the frame work for distributing the stress equally over the surface of the diaphragm from the axis pin during vibration and sound reproduction, incorporates a new principle in this full floating reproducing structure which is a departure over the prior art and is adapted to more efficiently and accurately reproduce sound 110 waves in the manner as above stated.

Having thus described my invention, what I claim as new is:—

A sound reproducing unit, comprising a housing, a sound reproducing structure having a full floating mounting on said housing, a casing slidable in said housing, electromagnetic means mounted in the casing operably associated with the sound reproducing structure adapted to operate said structure for reproducing sound waves, and a rod member rotatably mounted in the housing and having an eccentric connection with said casing operable to slide the casing in the housing in the rotation thereof for varying the volume of sound reproduction of said unit.

115 120 125 In testimony whereof I affix my signature.
PETER AMATO.
